(57) **CLAIM**

The ornamental design for an electronic device with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of an electronic device with graphical user interface showing the claimed design; and,

FIG. 2 is a front view of an alternate electronic device showing the graphical user interface of FIG. 1 applied thereto.

The outer broken lines in the figures show an electronic device having a display screen, or an alternate electronic device having a display screen, and form no part of the claimed design. The other broken lines in the figures show portions of the graphical user interface that form no part of the claimed design.
